LAMP CONSTRUCTION

Manuel Markowitz, Los Angeles, Calif.

Application January 27, 1941, Serial No. 376,118

6 Claims. (Cl. 240—81)

My invention relates to a lamp construction and more particularly to a lamp construction capable of providing a readily controlled degree of illumination.

It is frequently desirable to provide with a lamp a low degree of illumination, such for example as is sufficient to render objects visible yet insufficient to permit the reading of a printed page or to cause glare. A lamp providing such a comparatively low degree of illumination finds great utility in cafes and restaurants where it enables the diners to eat in comfort without detracting from the superior illumination of the entertainers. Such lamps are also widely employed as night lights for sleeping quarters, for illuminating the interior of vehicles, etc. It is an object of my invention to provide a lamp construction capable of supplying such a comparatively low degree of illumination.

In many of the fields of use of a lamp providing such a low degree of illumination it is frequently desired to secure from the same light source a high degree of illumination. Thus, for example, in cafes and restaurants it is of great advantage to, at times, provide a high degree of illumination from the lamp customarily employing the low degree of illumination, as hereinbefore described, in order that there may be read in comfort a printed page, such as menus or the like, and similarly it is of advantage that such a lamp construction also provide a high degree of illumination in sleeping quarters so that the same light source which is employed as a night light may be used as a reading lamp. Likewise it is advantageous to secure from a lamp in a vehicle ordinarily illuminating the interior thereof to such a low degree as not to detract from the visibility of the road ahead a higher degree of illumination for the reading of maps, etc.

It is an object of my invention to provide a lamp construction which is capable of illuminating a defined field to a low degree with soft diffused light and to a high degree with brilliant reflected light, and which is readily adjustable to vary the degree of illumination, providing an infinite number of gradations of light intensity between such low and high degrees.

More particularly it is an object of my invention to provide a lamp construction having thereon a diffusion member transmitting light from a light source and a reflecting member which reflects rays from such light source through and about such diffusion member with means for varying the proportion of the light from such source which is reflected above the light diffusion

member, so that the degree of illumination is varied.

In many fields of use of a lamp construction, such as above described, it is frequently desirable to vary the vertical dimensions of the field of illumination without varying the intensity of the illumination. Thus, for example, in a lamp construction for a table of a cafe or restaurant it may be desired to provide a vertical field of illumination, the low limit of which is the table top and the upper limit of which is the eye level of individuals seated at the table. This upper limit obviously will vary with individuals of different heights, making it necessary to vary the upper limit of the field of illumination if the eyes of different individuals are to be shielded from rays from the light source.

It is an object of my invention to provide a lamp construction defining the upper limit of the field of illumination and including means for easily adjusting this upper limit as may be desired.

Still another object of my invention is the provision of a lamp construction capable of providing a low degree of illumination and a high degree of illumination, with means for varying the degree of illumination between such limits and means for defining and varying the upper limit of the field of illumination.

In many fields it is desirable to employ a lamp construction providing a colored field of illumination, such, for example, as a blue field of low illumination in sleeping quarters, a blue field of high illumination where great visibility for precision work is required, and a red, orange, or yellow field of illumination for photographic processing. In such fields of use it is frequently desired to provide from the same light source a white field of illumination or a field of a higher degree of illumination.

It is a corresponding object of my invention to provide a lamp construction capable of furnishing a colored field of illumination and also capable of producing a white field of illumination of different intensity, with means for varying the color and degree of illumination of the field.

The lamp construction capable of accomplishing these and other objects and providing the foregoing and other advantages is described in the following specification, which may be better understood with reference to the accompanying drawings in which

Fig. 1 is an elevational view partially sectioned of one form of my invention;

Fig. 2 is a fragmentary sectional view taken as indicated by the line 2—2 of Fig. 1;

Fig. 3 is a sectional view taken as indicated by the line 3—3 of Fig. 2;

Fig. 4 is a vertical sectional view of another embodiment of my invention;

Fig. 5 is a fragmentary sectional view taken as indicated by the line 5—5 of Fig. 4;

Fig. 6 is a fragmentary plan view taken as indicated by the line 6—6 of Fig. 4;

Fig. 7 is a fragmentary vertical sectional view of the means embodied in the construction illustrated in Fig. 4 for elevating the shield or reflecting member;

Fig. 8 is a vertical sectional view taken as indicated by the line 8—8 of Fig. 7;

Figs. 9, 10, and 11 are fragmentary sectional views of alternative forms of reflector members which may be employed with the embodiment of my invention illustrated in Fig. 5;

Fig. 12 is a vertical sectional view of another embodiment of my invention adapted for illuminating the interior of vehicles;

Fig. 13 is a sectional view taken as indicated by the line 13—13 of Fig. 12; and

Fig. 14 is a sectional view taken as indicated by the line 14—14 of Fig. 12.

Referring to the drawings which are illustrative purposes only, the numeral 21 of Fig. 1 indicates one embodiment of a lamp construction of my invention. This embodiment includes a supporting stand 22 comprising two telescoping member 23 and 24. The member 23 is a hollow cylindrical member in which the member 24 is slidably disposed and is provided at its lower end with a base 25 of enlarged diameter. A set screw 26 is threaded through the lower telescoping member 23 against the upper or inner telescoping member 24 to secure it against vertical movement. An electrical conductor 27 passes through the base 25, the hollow cylindrical member 23, and the upper telescoping member 24 which is also a hollow cylindrical body, and is connected to a suitable light source. This light source may be a fluorescent lamp, a neon or tubular lamp, or a conventional incandescent light bulb. I have shown the conductor 27 as connected to a light socket 28 of conventional construction which receives a light bulb 29.

Mounted upon the socket 28 and in fixed relationship therewith is a lower reflector 30 substantially semi-spherical in form. The lower reflector 30 is provided with a horizontal flange 31 adjacent its upper edge with an upturned lip 32 extending therearound.

Positioned within the lip 32 and resting upon the horizontal flange 31 is a light diffusion or translucent member 33. The member 33 may be of any suitable outline conforming to the outline of the lip 32 and the horizontal flange 31, and is illustrated in Fig. 1 as circular in outline. It may be formed of any desired material having the property of transmitting light from the source 29 as a diffused soft light providing a relatively low degree of illumination and free of glare. I have found the material most suitable for this purpose to be glass, etched or sand blasted.

Secured to the outside of the lower reflector 30 adjacent the horizontal flange 31 is a plurality of horizontal ears 35, illustrated as two in number. Secured to each of the ears 35 and depending therefrom is an outer cylindrical sleeve 36, best illustrated in Fig. 2. Within each of the sleeves 36 is rotatably disposed a sleeve 37 hav-

ing an annular flange 38 engaging the upper surface of the associated ear 35. The sleeve 37 is provided with a cylindrical bore 39 into the lower end of which is threaded a plug 40 which is non-rotatably secured to a knurled knob 41.

Formed in the inner sleeve 37 and extending through a substantial part of its length is a spiral way 42 into which a horizontal pin 43 mounted upon a supporting rod 44 projects. The supporting rod 44 is slidably received in the cylindrical bore 39 of the sleeve 37 and is held against rotation by attachment to an upper reflector 45. Projecting upwardly from the upper reflector 45 is a rod 46 upon which a decorative top piece 47 is threaded to retain a shield or shade 48 in position against stop rods 49 attached to the top of the upper reflector 45. The shade 48 may be of any desired outline and shape and formed of any suitable material to provide a pleasing appearance, but is preferably extended slightly below the lower edge of the light diffusion member 33 when it is in its lowermost position, as illustrated in the full lines of Fig. 1.

With this embodiment of my invention and the parts thereof in the positions illustrated in the full lines of Fig. 1, all of the rays of light from the light source 29 are directed through the diffusion member 33, either directly from the light source or reflected from one or the other, or both, of the reflectors 30 and 45. The lamp 21 thus provides a soft diffused light free of glare, but of a sufficiently high degree of illumination to render adjacent objects visible. In this position the lamp 21 is suitable for use upon a dining table or in a sleeping room or the like.

When a higher degree of illumination is desired, the knurled knob 41 is rotated, thus rotating the sleeve 37 and causing the horizontal pin 43 to travel upwardly in the spiral way 42, carrying the supporting rod 44. I have illustrated only one of the supporting rods 44 as being positively actuated, although obviously, if desired, both of such rods may be actuated by the use of the construction illustrated in Fig. 2. This upward movement of the supporting rods 44 elevates the upper reflector 45 relative to the diffusion member 33, the light source 29, and the lower reflector 30. Such an elevated position of the upper reflector 45 and the shade 48 carried thereby is illustrated by the broken lines of Fig. 1. With the parts in this position undiffused light passes outward through the space between the upper reflector 45 and the diffusion member 33, this light including rays directly from the light source 29 as well as rays reflected by the lower reflector 30 or the upper reflector 45, or both of such reflectors.

With the parts in the position thus described, the light provided by the lamp 21 is a mixture of the diffused light passed through the diffusion member 33 and the more brilliant undiffused light which has passed between the upper reflector 45 and the diffusion member 33. The resulting illumination is of a much higher degree than that provided when all of the light emitted by the lamp passes through the diffusion member 33 and is sufficient to enable individuals near the lamp to read in comfort.

By loosening the set screw 26, the member 24 may be raised or lowered relative to the lower telescoping member 23 until the shade 48 defines the upper limit of the field of illumination at the desired level, which is preferably below the eye level of the individual adjacent the lamp.

The set screw is then tightened to hold the members 23 and 24 against relative movement.

If desired, as, for example, for use in some circumstances, such as hereinbefore described, the diffusion member 33 may be caused to provide a field of colored light by incorporating suitable coloring material within, or a coating upon, the diffusion member 33. Thus, for example, if the diffusion member 33 be coated with a red application, the lamp 21 is suitable for use in a photographic dark room. When the photographic process requiring such colored light is ended and a higher degree of illumination is desired, it is necessary only to elevate the upper reflector 45 in the manner previously described.

Figs. 4 to 8, inclusive, illustrate another embodiment of my invention, adapted for use in a table top. Referring to Fig. 4, the numeral 52 indicates a table top of opaque material, which may be of conventional outline, such for example as round or square, and which is supported upon a central pedestal 51, illustrated as cylindrical in form. At its lower end the pedestal 51 is provided with a foot member 52 of enlarged diameter, having an opening 53 therein.

Centrally of the table top 50 is a circular opening 54 in which an annulus 55 is removably positioned. The annulus 55 may be made of glass or material of the same type as the material forming the table top 50. The annulus 55 is secured to the upper end of a cylindrical shell 56, the lower end of which rests upon the upper surface of the foot member 52 within the pedestal 51. A housing 57 which may be semi-spherical in form is secured to the annulus 55 as by having an annular flange 58 extending from the rim of the housing 57 clamped between the upper end of the cylindrical shell 56 and the lower surface of the annulus 55. The shell 56, annulus 55, and housing 57 are thus attached together against movement relative to each other. Through a central opening in the housing 57 extends a hub portion 59 of a reflector 60. The reflector 60 is illustrated as semispherical in outline, having a lower horizontal flange 61 above the upper face of the flange 58 of the housing 57 and having an upper horizontal flange 62 recessed in the annulus 55 so that its upper surface is flush with the upper surface of the annulus 55.

Mounted in the hub portion 59 of the reflector 60 is a conventional light socket 63 receiving a light bulb 64 and connected to electrical conductors 65 which are attached to an electrical contact 66 which projects into a recess in the lower surface of the annulus 55 and is provided with a downwardly extending contact arm 67 outside of the cylindrical shell 56. The contact arm 67 extends through a slot in an insulating block 68 and into engagement with a spring contact arm 69 therein. The spring contact arm 69 is electrically connected through a conductor 70 with a source of current not shown, the conductor passing downwardly between the cylindrical shell 56 and the pedestal 51 and through the opening 53 in the foot member 52.

As illustrated in Fig. 4 the conductor 65 is of a length sufficient to permit the elevation of the reflector 60 and light socket 63 a considerable distance above the table top 50.

Resting upon the horizontal flange 61 of the reflector 60 is a diffusion member 71 similar to the diffusion member 33. It will be noted that the diffusion member 71 projects a short distance above the table top 50 and is adapted to transmit

rays radially of the table top 50 and substantially horizontal. Positioned upon the diffusion member 71 is a shield 72 which may be employed as a supporting means for food, condiments, ash trays, decorations, or the like. As illustrated in Fig. 4 the shield 72 includes a horizontal plane central portion 73 surrounded by an upstanding rim 74 with an outwardly declining flange 75 embracing the upper edge of the diffusion member 71. As illustrated in Fig. 5 the shield member 72 is supported upon two vertically movable arms 76 and 77; either or both of these arms may have connected thereto actuating means for moving the shield member 72 relative to the diffusion member 71. I have illustrated the arm 77 in Figs. 5 and 7 as having such actuating means and capable of such vertical adjustment. The arm 77 extends downwardly through a small housing 78 and a cylindrical tube 79 which communicates at its upper end with the housing 78 and is closed at its lower end. The tube 79 is received within a cylindrical shell 80 which passes downwardly through the annulus 55 and is firmly attached to the flange 62.

25. A shaft 81 extending through the housing 78 is provided with a knurled wheel 82 on an end thereof and a pinion 83 intermediate its ends and within the housing 78. The pinion 83 meshes with a rack 84 formed upon the supporting rod 77, so that, when the knurled wheel 82 is rotated, the pinion 83 meshing with the rack 84 causes the supporting rod 77 to move vertically with regard to the annulus 55 and the table top 50. By such actuation of the knurled wheel 82, which 30 may be easily accomplished by an individual seated adjacent the table top 50, the shield member 72 may be moved from the position illustrated in the full lines of Fig. 5 in which all of the light provided by the lamp construction is 35 transmitted through the diffusion member 71 into the position in which it is illustrated by the broken lines of the same figure where a space of substantial vertical dimension is provided between the upper edge of the diffusion member 71 and the lower surface of the shield member 72 through which light rays may pass to illuminate the table top without passing through the diffusion member 71. In this latter positioning the lamp construction provides that higher degree 40 of illumination previously described.

Slidably mounted in a boss 85 supported upon arms 86 secured to the interior of the cylindrical shell 56 is a connector in the form of a hollow tubing 87 which is attached to the reflector 60 and slidable through the central opening in the housing 57. The tubing 87 is provided with an offset portion 88 connecting at its lower end with a rack 89 slidably mounted for vertical movement in a housing 90. The housing 90 engages the portion 88 of the tubing 87 and guides it during vertical movement.

A shaft 91 journalled in one wall of the housing 90 and in the cylindrical shell 56 has mounted thereon a pinion 92 meshing with the rack 89 and a gear 93 meshing with a chain 94. The chain 93 extends upwardly and over a gear 94 mounted upon a shaft 95 journalled in the cylindrical shell 56 and a vertical bracket 96 secured to the inner wall thereof. A knurled wheel 97 is non-rotatably mounted upon the shaft 95 and is of a diameter such that it projects a short distance above the table top 50 through a slot therein. The rotation of the knurled wheel 97, which may be easily accomplished by one seated adjacent the table top 50, rotates the

shaft 95 and gear 94, and through the chain 93, the shaft 91 and pinion 92 thereon, thus moving the rack 89 vertically. This movement of the rack 89 causes vertical movement of the reflector 60, carrying with it the diffusion member 71 and shield member 72.

By such actuation of the knurled wheel 97, vertical movement of the elements just described is accomplished between the position indicated in the full lines of Fig. 5, in which the declining flange 75 of the shield member 72 defines the upper limit of the field of illumination relatively close to the table top 50, to the position illustrated by the broken lines of the same figure, in which the upper limit of the field of illumination is similarly defined at a greater height above the table top 50. It will be seen that, by the construction and actuation just described, this upper limit of the field of illumination may be readily adjusted and maintained below the eye level of individuals of different height.

Since the plane central portion 73 of the shield member 72 may be employed to support food, condiments, ash trays, decorations or the like, it will be seen that the installation of the lamp construction of my invention in the table top has diminished only to a negligible extent the area of the table top available for use. The shield member may be provided with varying degrees of heat insulation, depending upon the use to which it is put.

Thus in Fig. 9 I have shown a shield member 72^a provided with a layer of heat insulation 98 around the sides and bottom thereof, adapting the shield member for the storage of condiments or the like which must be maintained at a relatively low temperature and hence insulated from the heat generated by the light source 64.

In Fig. 10 I have illustrated a form of shield member indicated by the numeral 72^b which is devoid of heat insulation and is adapted for transmitting heat from the light source 64 to the contents of the shield member, such as peanuts or the like.

In Fig. 11 I have indicated by the numeral 72^c still another form of shield member, adapted for use as an ash tray.

If it is desired to remove the lamp construction illustrated in Figs. 4 to 8, inclusive, for inspection or repair, the entire construction may be removed as a unit by moving the annulus 55 upwardly, as illustrated by the broken lines of Fig. 4. This elevation of the annulus 55 serves to elevate the cylindrical shell 56 and the entire lamp construction, the contact 67 sliding over the contact arm 69, and thus eliminating the necessity of removing any electrical connections.

The diffusion member 71, like the diffusion member 33 previously described, may be constructed not only to transmit a soft diffused white light, but also to transmit a colored light of the desired characteristics as previously referred to, and it will be understood that the term "diffusion member," as employed herein, applies to constructions of both types.

The numeral 103 indicates another embodiment of my invention, illustrated in Figs. 12 to 14, inclusive. This embodiment is adapted for use in a passenger vehicle, such as a coupé, or sedan, or truck cab, or the like. The numeral 104 indicates the ceiling of such a vehicle, which is provided with a cylindrical opening 105 above which there is mounted a downwardly concave supporting member 106. The supporting member 106 may have its lower surface 107 polished,

plated, or coated to provide a reflecting surface, and supports centrally of the opening 105 a conventional light socket 108 connected in the usual manner to a source of potential. Secured in the socket 108 is a light bulb or light source 109.

Secured to the surface of the ceiling 104 around the opening 105 is an annular flange 110 of a housing 111 which includes a vertical cylindrical wall 112 extending into the opening 105. The cylindrical wall 112 is provided with a plurality of pin-receiving openings, illustrated as two in number, each of which includes an upper and a lower vertical slot 113 and 114, respectively, connected by a horizontal slot 115. The upper slot 113 communicates with the upper edge of the housing 111, and the lower slot 114 terminates near the lower edge of the housing 111. It should be noted that the vertical cylindrical wall 112 of the housing 111 is spaced radially inwardly of the wall of the opening 105.

Adapted for sliding movement upon the upper edge of the housing 111 and in the slots 113, 114, and 115 are horizontal end portions 116 of a supporting arm 117, the central portion of which is bent downwardly below the ceiling 104 and is attached at its middle to a sleeve 118. The sleeve 118 is provided with a depending vertical pin 119, and a washer 120 is positioned upon the pin against the lower face of the sleeve 118. Also positioned upon the pin 119 and engaging the washer 120 is an upwardly concaved diffusion member 121 having an annular horizontal flange 122. The diffusion member 121, which may be formed of material similar to that of the diffusion members 71 and 33 previously described, is secured in position by a central recessed portion 123 of a clamping member 124, clamping the diffusion member 121 against the washer 120. The clamping member 124 is mounted upon the pin 119 and retained thereon by a ring 125 extending through the pin 119. The ring 125 is movable from a horizontal position within the recessed portion 123 of the clamping member 124, as illustrated by the full lines of Fig. 12, to a depending position, illustrated by the dotted lines 126 of Fig. 12, in which latter position it may be easily grasped for rotating the diffusion member 121.

Secured around the peripheral edge of the diffusion member 121 and engaging the lower surface of the annular flange 122 is a protective and decorative rim member 127. An annular gasket 128 is secured to the upper surface of the horizontal flange 122, maintaining a light-tight relationship between the flange 110 of the housing 111 and the diffusion member 121 when the diffusion member 121 is in its uppermost position, as illustrated in Fig. 12. In this position all of the light from the light source 109 entering the vehicle passes through the diffusion member 121 with the result that the interior of the vehicle is illuminated to a relatively low degree, providing the minimum interference with the driver's vision of the road ahead and of his instruments.

When it is desired to illuminate the interior 65 of the vehicle to a higher degree, the ring 125 is moved to its depending position, illustrated by dotted lines 126, and rotated, thus causing the diffusion member 121 and the arm 117 to rotate until the horizontal portions 116 of the arm slide 70 downwardly in the upper slots 113 in the housing 111. The horizontal portions 116 of the arm 117 will then rest upon the lower walls of the horizontal slots 115, restraining the diffusion member 121 against further downward movement. 75 In this position an annular space of substantial

vertical dimension is provided between the flange 110 of the housing 111 and the annular gasket 128 through which light rays directly emitted from the light source 109 and reflected from the surface of the interior of the housing 111 pass radially and horizontally, illuminating the interior of the vehicle to a higher degree and providing sufficient illumination to permit the occupants of the vehicle to read a printed page, map, or the like.

Even a higher degree of illumination may be provided by further rotation of the diffusion member 121 and the arm 117 in the manner previously described until the horizontal portions 116 of the arm 117 slide downwardly in the lower vertical slots 114 of the housing 111. In this position of the diffusion member 121 an annular space of even greater vertical dimension is provided between the horizontal flange 110 of the housing 111 and the gasket 128, thus increasing the quantity of light which passes outward above the diffusion member 121 to illuminate the vehicle.

When the diffusion member 121 is placed in the desired position, the ring 125 may be forced upwardly into the recessed portion 123 of the clamping member 124.

With all the embodiments of my invention it will be seen that there can be provided a low degree of illumination, the light being soft and free of glare and a high degree of illumination suitable for reading purposes and the like and any desired degree of illumination between these limits.

It will further be seen that the lamp construction of my invention permits the ready adjustment of the vertical dimensions of the field of illumination independently of variations in the intensity of the illumination, so that the field of illumination may be made lower than the eye level of the individual.

Further, in the lamp construction illustrated in Figs. 1 to 3, inclusive, it will be seen that as the shade or shield 49 may be made with its inner surface of any desired degree of reflective quality, the character of illumination may be varied by elevating the shade relative to the diffusion member 33. Thus when the upper reflector 45 is spaced upwardly from the diffusion member 33, the light source provides an annular beam of light which impinges upon and is reflected from the inner surface of the shade 48. As the upper reflector 45 is moved vertically relative to the diffusion member 33, the direction of this annular beam of light remains substantially constant, but, while the shade 48 is being moved vertically relative to the light source 29, this beam impinges upon different portions of its inner surface. By forming the shade 48 so that its lower reflecting surface is curved, this change in location of the area of impingement of the annular beam thereon causes a change in the angles of incidence and reflection, changing the characteristics of the light reflected by the shade 48. This change in such characteristics may be controlled by the curvature of the shade 48 and movement of the shade 48 relative to the light source 29.

In the embodiments illustrated in Figs. 1 and 4 the shade or shield may be mounted on a universal or ball and socket joint suitably supported on the rod 46 or a central rod carried by upwardly converging arms on the reflector 69, so that the light passing through or above the diffusion members 33 or 71 on opposite sides thereof may be varied in inverse relation by tilting the shade 75

or shield, a construction particularly useful for display and the like when the diffusion member is colored to diffuse light unlike daylight, and the light source is such as to provide light above the diffusion member like daylight.

With particular reference to the embodiment illustrated in Figs. 4 to 11, inclusive, it should be noted that the light provided to the table top 50 consists of a radial beam which is substantially horizontal and that this beam illuminates the annular field of the table top. Such beam provides illuminating effects different from those secured by an overhead light source such, for example, as the shadows cast by articles thereon and has an upper boundary inclining outwardly from the light source, so that at the periphery of the table top it is below the eye level of individuals seated at the table. The depending flange 75 of the shield member 73 may be so designed and the light source 64 so positioned relative to the table top 50 that the light source 64 cannot be seen by individuals seated at the table, and there is no reflection of the light source on the table top visible to such individuals.

While those embodiments of my invention hereinbefore illustrated and described are fully capable of performing the objects and providing the advantages primarily stated, there are various modifications which may likewise perform these objects and provide these advantages. For example, the embodiment illustrated in Figs. 1 to 3, inclusive, may be provided with a supporting stand adapting the construction for use as a floor lamp, bridge lamp, or the like, instead of a table light. Likewise the embodiment illustrated in Fig. 4 may be used as a wall light, and the embodiment illustrated in Fig. 12 may be employed as a wall lamp recessed therein or supported on a bracket attached thereto, or may be employed as a table lamp.

I claim as my invention:

1. In a lamp construction, the combination of: a supporting stand including telescoping members; a light source on said stand; a reflecting member fixed to one of said members adjacent said light source; a movable reflector; a light diffusion member disposed to receive rays of light directed from said light source otherwise than toward said reflecting member and said reflector; and rays of light reflected from said reflector; and means adjustably connecting said reflector to said reflecting member whereby said reflector may be secured between position adjacent said diffusion member and position substantially spaced therefrom, the area of said diffusion member receiving light directly from said light source being the same for each of said positions.

2. In a lamp construction, the combination of: a supporting stand including telescoping members and locking means releasably securing said members against relative movement; a light source on said stand; a reflecting member fixed to one of said members adjacent said light source; a movable reflector; a light diffusion member disposed to receive rays of light directed from said light source otherwise than toward said reflecting member and said reflector; and rays of light reflected from said reflector; and means adjustably connecting said reflector to said reflecting member whereby said reflector may be moved from position directing all of its reflected light through said diffusion member to position directing a substantial portions of its reflected light around said diffusion member, the area of said diffusion mem-

ber receiving light directly from said light source being the same for each of said positions.

3. In an illuminator, the combination of: an upwardly opening first bowl-shaped opaque reflector; a light source; a cylindrical shell incompletely transmissive of light, disposed with its lower edge contiguous to the edge of said first reflector; a downwardly opening second opaque bowl-shaped reflector vertically movably mounted with respect to said light source, shell, and first reflector and normally disposed with its edge contiguous to the upper edge of said shell; and means for vertically moving said second reflector relative to said shell to provide an annular opening therebetween through which light rays may be 15 relatively completely transmitted.

4. In an illuminator, the combination of: an upwardly opening first bowl-shaped opaque reflector; a light source; a cylindrical shell incompletely transmissive of light, disposed with its lower edge contiguous to the edge of said first reflector; a downwardly opening second opaque bowl-shaped reflector vertically movably mounted with respect to said light source, shell, and first reflector and normally disposed with its edge contiguous to the upper edge of said shell; means for vertically moving said second reflector relative to said shell to provide an annular opening therebetween through which light rays may be 20 relatively completely transmitted; and a downwardly opening third bowl-shaped reflector spaced outside of and mounted to move with said second reflector and disposed with its lower edge below the lower edge of said second reflector.

5. In an illuminator, the combination of: an upwardly opening first bowl-shaped opaque reflector; a light source; a cylindrical shell adapted for the transmission of only colored light, disposed with its lower edge contiguous to the edge of said first reflector; a downwardly opening second opaque bowl-shaped reflector vertically movably mounted with respect to said light source, shell, and first reflector and normally disposed with its edge contiguous to the upper edge of said shell; and means for vertically moving said second reflector relative to said shell to provide an annular opening therebetween through which light rays may be 25 relatively completely transmitted.

6. In an illuminator, the combination of: an upwardly opening first bowl-shaped opaque reflector; a light source; a cylindrical shell incompletely transmissive of light, disposed with its lower edge contiguous to the edge of said first reflector; a downwardly opening second opaque bowl-shaped reflector vertically movably mounted with respect to said light source, shell, and first reflector and normally disposed with its edge contiguous to the upper edge of said shell; and means for vertically moving said second reflector relative to said shell to provide an annular opening therebetween through which light rays may be 30 relatively completely transmitted, said reflector, said source, and said shell being so disposed that rays directly from said source and rays reflected by said second reflector may pass through said annular opening.

MANUEL MARKOWITZ.
